Attorney

UNITED STATES PATENT OFFICE.

WALTER M. BLACK, OF EATON, INDIANA.

FLOAT VALVE.

Application filed November 21, 1921. Serial No. 516,557.

To all whom it may concern:

Be it known that WALTER M. BLACK, a citizen of the United States, residing at Eaton, in the county of Delaware and State 5 of Indiana, has invented certain new and useful Improvements in Float Valves, of which the following is a specification.

This invention relates to improvements in float valves of the type employed for automatically governing the flow of a liquid from a relatively superposed source of supply to a lower outlet receptacle, the construction of the valve being such as to automatically maintain a substantially uniform 10 liquid level in a receptacle and to replenish the same from said source of supply as the liquid is used for various purposes. An object of the invention resides in the provision of a float valve capable of being adapted 15 for use in conjunction with farm stock, watering troughs, for the purpose of maintaining a desired water level in such troughs.

Another object of the invention resides in an automatic float wherein the liquid supply 20 passes through the float and is controlled by a valve located beneath the float and responsive to the rise and fall of the latter. In many prior devices, the floats proper are located beneath the valve structure 25 and required guides of a relatively fixed character which are likely to cause irregular operation on the part of the floats. By the present invention, the float is guided by an axially extending support through which 30 water or other liquid from a relatively elevated source of supply is longitudinally 35 passed.

For a more complete understanding of the invention, reference is to be had to the 40 following description and the accompanying drawing, in which similar characters of reference denote like and corresponding parts throughout the several views thereof.

In said drawing:

Figure 1 is a vertical sectional view taken 45 through the improved float valve comprising the present invention, and disclosing its adaption to the watering trough.

Figure 2 is a horizontal sectional view 50 taken on the plane indicated by the line 2—2 of Figure 1, and,

Figure 3 is a top plan view of the float.

Referring more particularly to the details 55 of the invention, there is provided a float valve structure designated generally by the numeral 1. In its preferred form, this

structure consists of a metallic float 2, which includes a semi-spherical body 3 having a convexed top 4, which is united in a fluid tight manner with the body 3 by the 60 interfitting peripheral beads 5. Extending axially and vertically through the float 2 is a tube 6, having its upper end secured as at 7 to an upstanding collar 8 integrally formed with a top 4. The lower portion of 65 the tube 6 is relatively enlarged as at 9 and an annular shoulder 10 is thereby formed at the juncture between the upper and lower portions of the tube 6.

The enlarged lower end of the tube projects 70 axially through and is suitably secured to a depending tubular extension 11 integrally formed upon the lower axial part of the body 3, the extreme lower end of said tube being materially spaced from the lower end 75 of the float proper. In this depending extreme lower end of the tube 6, which is designated by the numeral 12, there is provided a plurality of ports 13, and beneath the ports the end 12 is threaded as at 14 for the 80 reception of a closure cap 15. A rubber or other gasket 16 is confined between the inner part of the cap 15 and the lower edge of the tube 6. This gasket may be renewed from time to time by the mere removal of 85 the cap 15 which, by being threaded to the end 12, can be readily effected.

Arranged to extend axially into the tube 6 is a stationary liquid supply pipe 17 which has its upper end connected or in communication 90 with a suitable source of liquid supply in order that liquid, by the action of gravity will be permitted to flow through said pipe. The lower end of the pipe 17 is threaded as at 18 for the reception of a 95 relatively enlarged collar 19, which is situated within the enlarged portion 9 of the tube 6, and by reason of the threaded connection 18, it will be apparent that the collar 100 19 may be adjusted relatively to the gasket 16. It will be apparent that by this construction the rise and fall of the float 2 will 105 control the relationship between the gasket 16 and the lower end of the collar 19, thereby, in turn, governing the flow of liquid through the ports 13. In the use of the valve shown in the accompanying drawing, there is provided a stock watering trough

wherein is included a superposed water receptacle 20 to the lower part of which the 110 upper end of the pipe 17 is connected. The float structure 2 is situated for vertical

movement within the float chamber 21 of the watering trough 22, and is separated from the drinking chamber 23 of said trough by means of an apertured partition wall 24. When thus employed, it will be apparent that water from the receptacle 20 will be permitted to flow by gravity into the chamber 21, passing through the ports 13, and from the chamber 21 the water will pass 10 into the drinking chamber 23 by way of the apertures in the wall 24. When the water level within the chambers 21 and 23 reaches a predetermined height, the float, by reason of its buoyancy, will rise in the chamber 21 15 until the gasket 16 abuts upon the lower end of the collar 19, thus shutting off further water flow from the receptacle 20 into the trough 22. As the water in the chamber 23 is consumed, the valve structure will automatically operate, in an apparent manner 20 to maintain a uniform level in the chamber 23 as long as the receptacle 20 is supplied with the requisite amount of liquid. It is to be understood, however, that while the 25 valve structure may be admirably utilized in a watering trough of this character, nevertheless, the said valve structure is capable of being employed for numerous other uses with the same degree of facility and efficiency, and therefore such other uses will not depart from the spirit and intent of the 30 present invention. It will be noted particularly that the float is mounted for vertical movement upon the longitudinally and axially extending pipe 17, which passes centrally through the float and serves in the 35 capacity of a guide for controlling the movements of the float while the latter is responding to the rise and fall of the water level in the associated receptacle. It will be noted 40 particularly that the float is not provided

with peripheral guides, common in many prior structures and that in the present construction water or liquid will flow centrally through the float and not around the same. 45 Again, positive action on the part of the valve structure is secured by the absence of undue friction between the float and its guide so that sticking of the float in such manner as to render the same uninfluenced 50 by water level, will be precluded. The location of the valve beneath the float, instead of over the same is also an added structural advantage.

What is claimed is:

1. A float valve structure comprising a hollow buoyant float member, a tube arranged to extend axially through said float member and to project beneath the same, the said lower projecting end of said tube being 60 provided with a port, a closure for the lower end of said tube, a stationary liquid supply pipe extending into said tube, and an adjustable sleeve carried by the lower end of said pipe and movable toward and away from 65 said closure.

2. A float valve consisting of a float member, a tube extending axially through said float member, the lower end of said tube being relatively enlarged and arranged beneath said float member, the enlarged lower end of said tube being provided with ports, a cap threaded upon the lower end of said tube, a gasket between said cap and the lower end of said tube, a liquid supplying pipe extending axially of said tube, and a collar adjustably carried by the lower end of said pipe and adapted for cooperation 75 with said gasket.

In testimony whereof I affix my signature.

WALTER M. BLACK.
